(57) **CLAIM**

The ornamental design for a box for truck wheel well, as shown and described.

DESCRIPTION

FIG. 1 is a front, top, right side perspective view of a box for truck wheel well;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a front, top, right side perspective view thereof, shown in a condition of use;

FIG. 9 is a front, top, right side perspective view of a second embodiment of a box for truck wheel well;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a front, top, right side perspective view thereof, shown in a condition of use.

The dash-dot broken lines in FIGS. 8 and 16 depict environmental subject matter and the dash-dot broken lines depict unclaimed portions of the design only and form no part of the claimed design.

1 Claim, 16 Drawing Sheets
